UNITED STATES PATENT OFFICE.

JOEL B. HAYDEN, OF HEMPSTEAD, ASSIGNOR TO FANNIE J. HAYDEN, OF SAME PLACE, AND FREDERICK J. HOYT, OF NEW YORK, N. Y.

FAUCET AND CAP.

SPECIFICATION forming part of Letters Patent No. 224,904, dated February 24, 1880.

Application filed July 1, 1879.

To all whom it may concern:

Be it known that I, JOEL B. HAYDEN, of Hempstead, county of Queens, and State of New York, have invented a new and useful Improvement in Faucets and Caps for Closing the Orifices in Liquid-Packages, of which the following is a specification.

The invention relates to the introduction of the faucet into the package when filled with out danger of the escape of the contents in the operation, and when the faucet is removed closes the orifice automatically, leaving the package in proper shape to be again refilled, thus saving the expense of plugs, corks, &c., and the necessary injury to the heads of the package in driving in plugs and removing from the inside of the barrel the plug driven in by the faucet, as in the present method. This invention is intended to apply more directly to lager-beer and ale barrels.

Heretofore in ale and lager-beer barrels it has been usual to plug the hole in the head with a wooden plug or cork, driven in tight enough to resist the pressure of the gas generated inside, and yet of proper size that the faucet can be introduced by driving the plug or cork through the orifice and into the package. This is objectionable, as unless very skillfully driven a quantity of the ale or beer is wasted. The forcing of the plug through the orifice wears and splits the head, necessitating in almost every case of refilling the putting in of parts of heads in each keg or barrel. Great difficulty and expense are experienced in removing the plugs or corks from the empty package before refilling.

The object of my invention is to provide a suitable device in combination with a faucet so that the faucet can be introduced into the head of a lager-beer or ale barrel without wastage of the contents, and when the faucet is removed the orifice is closed automatically, ready for refilling, doing away entirely with plugs, corks, &c., and the expense and trouble incidental to their present use. This I accomplish in the following manner, reference being had to the accompanying drawings, in which—

Figure 1 represents a side view of faucet, bushing, cap, and section of barrel-head. Fig.

2 represents a vertical cross-section of faucet, bushing, and cap. Fig. 3 represents an end view of cap D, showing slot F.

A represents the faucet; B, section of barrel-head; C, the bushing; D, the cap; E, the threaded reducer and shoulder; F, slot in bottom of reducer E; G, the perforations in faucet A, near its extremity; H, the perforations in cap D.

After boring a hole of suitable size through the head of a barrel I introduce into the hole the bushing C, threaded externally and internally, of sufficient length to pass through the head of the barrel and into the package one-half inch or more. The thread on the outside screwing into the wood binds and holds bushing C into the orifice in the barrel firm and tight. The thread on the inside of bushing C is for receiving faucet A, which is correspondingly threaded, and when screwed in is tight and firm, without leakage. On the inside of the package I place cap D, with shoulder on the inside, and reducer E, threaded in cap D and in reducer E to correspond with the threads upon the outside and inside of bushing C. The cap D is introduced into the barrel and screwed onto bushing C through the bung-hole in barrel.

When cap D is adjusted onto the end of bushing C and screwed up tight by means of a screw-driver worked in slot F in bottom of reducer E it closes perfectly air-tight the orifice. The threads upon the inside of bushing C and inside of reducer E are uniform, and form a continuous thread through bushing C and reducer E to the bottom, cap D having near its outer surface or face edge perforations H.

Bushing C and cap D are fastened permanently in the head of barrel. In connection with bushing C and cap D, I use a faucet, A, threaded the proper distance to correspond with the threads on the inside of bushing C and reducer E, said faucet A having slots or perforations G near the extremity of its threaded end.

The operation of the device is as follows: The cap D being screwed up tight on bushing C on inside of barrel, the barrel filled with beer, ale, or other liquids, faucet A is introduced into

bushing C from the outside or open end and screwed up until it has passed through bushing C into and to the bottom of reducer E. The operator then keeps turning or screwing 5 in faucet A, which revolves cap D on the thread on outside of bushing C and inside of the barrel a sufficient distance, which is controlled by the length of thread cut on faucet A, cap D being carried back and off of bushing C until 10 the perforations H in cap D extend beyond the end of bushing C in the barrel, when the ale or liquid immediately passes through the perforations H in cap D and slots or perforations G in faucet A, and is then drawn off in 15 the usual manner; or cap D may be run entirely off bushing C and the liquid pass directly into faucet A through slots or perforations G. When the barrel is empty or it is desired to remove the faucet the action of un- 20 screwing the faucet revolves and screws up the cap until the orifice or perforations in same are closed by the bushing and the orifice in the barrel is closed sufficiently to prevent leakage, and is again ready to be refilled. 25 The cap can be adjusted as tight as desired after removal of the faucet by a screw-driver used in slot F, sunk in bottom of reducer E.

Slot F in bottom of reducer E to cap D is for the purpose of tightening cap D firmly onto bushing C, providing the action of removing 30 the faucet A does not screw it entirely tight, and also to adjust cap D to its place on bushing C when cap D is passed through the bung-hole, and by proper device held up to and against bushing C on the inside of old barrels. 35

I am aware that a metal tube threaded outside is in use in the bung of lager-beer and ale barrels, and therefore do not make any special claim on the threaded bushing.

Having thus described my invention, I claim 40 as new and desire Letters Patent therefor—

The combination of a metal cap, D, having a shoulder and threaded reducer, E, with the screw on the extreme end of faucet A, in connection with a bushing externally and internally screw-threaded, the cap D being internally threaded to correspond therewith, substantially as set forth.

JOEL B. HAYDEN.
